Augustus H. Andrews,

BY

John J. Thompson
ATTORNEY.

UNITED STATES PATENT OFFICE.

AUGUSTUS H. ANDREWS, OF LANCASTER, PENNSYLVANIA.

CIGAR-RETAINER AND INNER SEAL.

No. 921,938.

Specification of Letters Patent.

Patented May 18, 1909.

Application filed September 15, 1908. Serial No. 453,097.

To all whom it may concern:

Be it known that I, AUGUSTUS H. ANDREWS, a citizen of the United States, residing at Lancaster, in the county of Lancaster 5 and State of Pennsylvania, have invented certain new and useful Improvements in Cigar-Retainers and Inner Seals, of which the following is a specification, reference being had thereto to the accompanying drawing.

My invention relates to an improved retainer or inner seal for packing cigars in boxes and holding the cigars under a tension, whereby the danger from the cigars becoming broken in shipment owing to their having 15 become loosened in the box on account of the natural shrinkage due to having been packed some time before shipment is obviated.

The objects of the invention are to produce a simple, cheap and effective retainer and inner seal combined, such that when the cigars are first packed in the box the retainer may be placed in position, but not 25 secured until it is desired to seal and ship the goods, when the retainer may be secured and thus tightly retain the cigars without regard to how loose they have become in the box since having been packed due to the 30 natural shrinkage.

Another object of the invention is that after the retainer (which is made preferably of glazed transparent paper) has been sealed, the cover of the box may still be opened and 35 the contents seen through said retainer without its being possible to remove or substitute the contents, and it may here be remarked in this regard that the internal revenue stamp might be used in the same 40 way as a seal for the retainer.

While another advantage of my improved combined retainer and inner seal is that as it is secured when the cover of the box is open, when said box cover is closed it creates 45 a pull upon the retainer which constitutes a tension and pressure upon the cigars, which will allow of their continued shrinkage without becoming loosened in the box; and further, by the use of this retainer and seal 50 the box may be opened, but the contents cannot be tampered with without destroying said seal; and further, as the seal is secured upon the outside of the box, all danger of paste coming into contact with the cigars is 55 avoided.

With these and other objects in view my

invention consists in certain construction and combination of parts as will be herein-after fully described and claimed, but it is fully understood that while I have herein 60 with described and illustrated my invention as applied to the packing of cigars, it may be put to many other uses, and slight changes may be made in the construction and arrangement of the parts without in any way departing from the spirit of the invention.

In the drawings forming part of this specification like reference characters designate corresponding parts in all the views.

Figure 1, is a perspective view of a cigar 70 box open and showing my improved combined retainer and inner seal in place. Fig. 2, is a perspective view of the back of a cigar box with the cover raised and showing the method of securing or sealing the retainer. 75 Fig. 3, is a cross section of a box of cigars open and shows the retainer secured in place before any tension is applied. Fig. 4, is a cross sectional view of a box of cigars with 80 the cover closed and showing the position of the retainer and cigars when the tension caused by closing the cover of the box is applied.

In the drawings:—Figs. 1, and 2, indicate a cigar box of the usual form except that the 85 back 2, just below the hinge-joint and under the binding 3, is provided with a slot 4.

To the bottom of the box, near the back thereof, is pasted or otherwise secured one end 7, of a retainer 5, which may be made of 90 any suitable material, but here shown and described as consisting of glazed transparent paper and which is of a width to correspond to the length of the box and of sufficient length to cover the bottom of the box, the 95 front side and extend back over the top layer of cigars and reach within a short distance of the back of said box. Secured to the free end of said retainer and forming part of the same is the seal or tongue 6, which is inserted 100 through the slot 4, drawn up over the joint of the cover 1, and pasted down upon the cover 1, near the joint, but in such a manner as to leave the end of said seal free. The slot 4, and seal where it covers the joint are 105 covered by the binding strip 3, which is pasted down over them and entirely concealing said slot 4.

The manner and use of the retainer and seal are as follows:—The retainer being secured by its end 7, to the bottom of the box 110 at the rear thereof, and covering the bottom

and front, the cigars are now placed within said box, and if it is desired to ship same at once the retainer is carried over the top layer of cigars and the seal or tongue inserted 5 through the slot in the back of the box, and drawn up and secured upon the cover 1, when said cover 1, is in an open position as shown in Fig. 3. The retainer and seal having been stretched in a comparatively tight 10 manner the seal is pasted to the box cover 1, adjacent to the joint with the back, in such a manner that the end of said seal is not attached. The joint of the cover is now bound with the usual binding 3, which will cover 15 the seal where it enters the slot 4, and conceal said slot from view. The cover of the box is now closed and secured and the action of said closing will exert a further pull upon the tongue or seal and tend to exert a tension 20 upon the retainer and thus hold the cigars in a close relation with each other and with the bottom and back of the box. Or if it is desired to retain the cigars for a while in stock, the seal may be inserted through the slot, the 25 cover closed, but said seal left free until such time as it is desired to seal, stamp and ship said box, when the retainer may be drawn up tight and the seal secured in place.

Having thus described my invention what 30 I claim as new and desire to secure by Letters Patent is:—

1. A combined retainer and inner seal for securing cigars within a box, comprising a band having one end secured to the bottom 35 of said box, a tongue formed upon the other end of said band and adapted to extend

through the side of said box and be secured to the outer surface of said box, all for the purpose of embracing and securing the cigars within said box.

2. In a device of the class described, in combination with a cigar box, a cigar retainer having one end secured within and to the bottom of said box and its opposite end extending through said slot and adapted to 45 be secured upon the cover of said box.

3. In a package for containing cigars, a retainer and inner seal comprising a band having one end thereof secured to the bottom of said box, said band extending forward under 50 the cigars, upward past the ends of the cigars and backward over the top of the cigars and through the slot in the side of said box and secured upon the cover of said box.

4. A cigar retainer and inner seal for securing cigars within a box, consisting of a band having one end secured to the bottom and within said box, a tongue formed upon the other end of said band and adapted to extend through the back of said box and be 60 secured to the cover of said box when said cover is in an open position for the purpose of embracing and exerting a retaining pressure upon the cigars when the cover of said box is in a closed position.

In testimony whereof I affix my signature in presence of two witnesses.

AUGUSTUS H. ANDREWS.
